DESIGN FOR A WHEELBARROW

David E. Staub, Detroit, Mich., assignor to Allied Manufacturers, Incorporated, Ypsilanti, Mich., a corporation of Michigan

Application January 23, 1939, Serial No. 82,538

Term of patent 14 years

To all whom it may concern:

Be it known that I, David E. Staub, a citizen of the United States, residing at Detroit, in the county of Wayne and State of Michigan, have invented a new, original, and ornamental Design for a Wheelbarrow, of which the following is a specification, reference being had to the accompanying drawing, forming part thereof.

Fig. 1 is a plan view of a wheelbarrow showing my new design.

Fig. 2 is a side elevation thereof.

I claim:

The ornamental design for a wheelbarrow, as shown,

DAVID E. STAUB.
